UNITED STATES PATENT OFFICE.

DOMENICO BRUNELLI, OF PHILADELPHIA, PENNSYLVANIA, ASSIGNOR OF ONE-HALF
TO GENEROSO DI GIACOMO, OF PHILADELPHIA, PENNSYLVANIA.

CLOCK CONTROL FOR TALKING-MACHINE RECORDS.

Application filed February 15, 1923. Serial No. 619,191.

To all whom it may concern:

Be it known that I, DOMENICO BRUNELLI, a subject of the King of Italy, residing at Philadelphia, in the county of Philadelphia 5 and State of Pennsylvania, have invented certain new and useful Improvements in a Clock Control for Talking-Machine Records, of which the following is a specification.

10 This invention appertains to a clock control for talking machine records.

The principal object of the invention is to provide in combination, a conventional type of alarm clock positioned in an opening in 15 the casing of a talking machine having a turn-table rotatably mounted therein, a lever in frictional contact with the rim of said turn-table and mechanism connecting the alarm mechanism of said clock with said 20 lever so that when said alarm releases, at a predetermined time, said lever will be withdrawn from contact with said turn-table permitting it to rotate.

Other objects will appear in the specifications and claims hereinafter contained.

For a full understanding of the invention and the merits thereof and also to acquire a knowledge of the details of construction and the means for effecting the result, 30 reference is to be had to the following detail description and the accompanying drawings.

While the invention may be adapted to different forms and conditions by changes in the structure and minor details without 35 departing from the spirit or essential features thereof, still the preferred embodiment is shown in the accompanying drawings, wherein:—

40 Figure 1 is a front view of a clock of the conventional alarm type positioned in the casing of a talking machine, said casing being broken away;

Figure 2 is a sectional view on line 2—2 of Fig. 3, illustrating the clock and its connecting mechanism to control the rotation of the turn-table of a talking machine; and

45 Figure 3 is a plan view, with the lid raised, of the device shown in Fig. 2.

Like reference numerals refer to like parts 50 throughout the several views.

Referring to the drawings in detail the numeral 10 represents the casing of a talking machine provided with a lid 11 for access to the interior thereof. A turn-table 55 12 is rotatably mounted within said casing

10 and is adapted to be rotated by motor means (not shown), within the body of the casing 10.

A vertically extending lever 13 is mounted on a shaft 14' journaled in a bearing 14 60 mounted on the transverse arms 15—15 secured to the inwardly projecting extensions 10^a—10^a from the casing 10. The lever 13 extends through a guide plate 24 and is positioned, substantially, parallel with the 65 inner wall of the casing 10.

The lever 13 at its base has an integral extension 16 which extends laterally therefrom and at a slight downward angle. An opening 18 is provided in the outer terminal of 70 said extension 16 in which is secured one end of a chain 17 the opposite end of said chain 17 being secured to a spool, or wheel 19.

A clock 20, of a conventional alarm type, having the clock face 26 and alarm setter 75 27 is suitably positioned in an opening in the front wall of the casing 10, substantially, centrally thereof, with the clock face 20 showing on the exterior of said casing.

An arm 21 is secured to the back of the 80 clock 20, and is provided with an integral right angled extension 21^a. A shaft 22 is journaled in the extension 21^a and the opposite end of said shaft 22 is journaled in the alarm mechanism in the back of the clock 20. 85 A wheel 19 is mounted on said shaft 22 and is adapted to rotate therewith. To this wheel 19 is secured the lower end of the chain 17.

In operation:—The normal position of 90 the lever 13 is as shown in solid lines in Fig. 2, the boss 23 on the said lever 13 impinging against the outer rim of the turn-table 12 and this frictional contact prevents the rotation of said turn-table 12 when the usual control thereof is released.

95 The alarm on the clock 20 is set to release at a predetermined time. When this time arrives the alarm is released rotating the shaft 22 which in turn rotates the wheel 19, 100 mounted thereon, in the direction indicated by the arrow in Fig. 2, winding the chain 17 on said wheel 19 which will cause the lever 13 to assume the position shown in dotted lines in Fig. 2, said lever 13 being adapted 105 for such movement on the shaft 14'. As soon as the boss 23 loses contact with the rim of the turn-table 12, said turn-table will rotate. When it is desired to again place the boss 23 in frictional contact with the 110

rim of the turn-table 12, the said lever 13 is pushed forward manually by means of the knob 28 thereon until such contact is had. A spring 25 tends to limit the forward movement of said lever 13. As the lever 13 travels forwardly the chain 17 unwinds from the wheel 19.

Having thus described my invention what I claim as new and desire to secure by 19 Letters Patent is:—

1. In a device of the character described, a casing, a horizontal rotatable turntable within the casing, a vertically swinging bell-crank lever pivoted within the casing near the turntable, said bell-crank lever embodying a generally vertical arm and a generally horizontal arm, the generally vertical arm being adapted to project above the turntable when in the active position so that it may be manually operated, a friction stop element carried by the generally vertical arm above its pivot and adapted to move vertically into engagement with the periphery of the turntable and also below the same to 25 disengage therewith, and time controlled

mechanism connected with the generally horizontal arm of the bell-crank lever to move the same.

2. In a device of the character described, a casing having a horizontal turntable in its upper portion, a horizontal rockshaft mounted within the casing beneath the turntable and extending radially with relation thereto, a generally vertical arm carried by one end of the rockshaft to swing in a vertical plane adjacent to the periphery of the turntable and projecting above the same to be manually operated, a friction stop element carried by the arm above the rockshaft to engage with the periphery of the turntable and to be shifted downwardly out of engagement therewith, a generally horizontal arm arranged within the lower portion of the casing, and secured to the inner end of the rockshaft, and time controlled mechanism mounted within the lower portion of the casing and connected with the generally horizontal arm.

In testimony whereof I affix my signature.
DOMENICO BRUNELLI.
